SPREADER CAP FOR ADHESIVE CONTAINERS

George E. Nealand, Newburyport, Mass., assignor
to The Carter's Ink Company, Cambridge,
Mass., a corporation of Massachusetts

Application November 18, 1935, Serial No. 50,254

3 Claims. (Cl. 91—67.5)

The invention relates to spreader caps for adhesive containers, especially containers for mucilage.

The object of the invention is to provide a normally sealed spreader cap but one in which the seal is readily broken at any time as the spreader is used, permitting escape of the adhesive content, or mucilage, to be spread; and which permitted escape of the mucilage is so free as will enable an unbroken film of mucilage to be applied to the object, or surface, acted upon as the spreader is drawn over it, but without such operation as will permit any of the mucilage remaining unspread.

The invention can best be seen and understood by reference to the drawing, in which—

Fig. 1 shows in side elevation a bottle fitted with the improved spreader cap.

Fig. 2 is a front elevation thereof.

Figs. 3 and 4 are vertical sections of the spreader cap.

Fig. 5 is a section of the spreader cap, and part of the bottle, showing the application and changed form of the cap when in use to allow the content of the bottle to escape.

Fig. 6 is a front elevation of a detail of construction later to be referred to; and

Fig. 7 shows in side elevation a slightly modified structure of the spreader cap.

The spreader cap, made of rubber, or equivalent elastic material, comprises a body 1, and tip 2 in extension from the body and bendable thereon. The bottom sectional part 3 of the body 1 is made in form suitable to fasten onto, and grip, the top flanged end 4 of a bottle 5, substantially as shown in Fig. 5.

Above its sectional part 3, and above the top end of the bottle when the cap is in place, the body of the cap has the general form of the frustum of a cone. Its sides 6, 6 are rounding. Its back 7 is substantially straight. Its front 8 is shaped to provide a flat spreading surface 9 having abrupt inward inclination in the direction of the back. The sides 6, 6 and back 7 are made relatively thick so as to be substantially inflexible, preventing collapse of the cap when in use, and forming a stationary base on which the tip may turn. The front portion 8 of the body having the spreading surface 9 is, also, made relatively thick in its lower portion, but gradually lessening in thickness towards its upper end for purpose later to be referred to.

The tip 2 of the cap is integral with the body 1. The tip is made, preferably, of about the thickness of the back 7 of the body from which it upwardly extends. The width of the tip is sub-

stantially that of the top end of the body, and is provided with parallel sides 10, 10, into which the sides 6, 6 of the body are merged. The back surface of the tip is substantially flush with the back surface of the body in continuation thereof. The front of the tip presents a spreading surface 11 conjoint with the spreading surface 9 on the body and having normally obtuse angular relation thereto, but becoming substantially flush therewith, when the tip is bent back as shown in Fig. 5. 10 The top of the tip presents a square edge.

As will be observed, the purpose is to obtain a spreader cap the body of which is non-collapsible, but which body is provided with a flexible tip, or head, care being taken that the tip may be flexed 15 and the spreading surface 11 thereof brought into alignment with the spreading surface 9 of the body without material change in the form of the chamber 12 within the body.

A slit 13 is made within the spreading surface 20 9 of the body at a point just below the tip and top end of the chamber 12 of the body. This slit is one normal to the axis of the cap. The slit is centrally disposed and is a relatively short slit, the ends of the slit being well removed from the 25 sides of the spreading surface 9 within which the slit is made. The slit 13 forms the mouth through which the contents of the bottle is emitted on inverting the bottle, and opening the slit. The slit is opened by inverting the bottle and bringing 30 the tip of the cap into contact with the object, or surface, to be acted upon, and then bending the tip back until its spreading surface 11 is flush with the spreading surface 9 of the body. As the tip is turned back the slit will be opened with a 35 relatively large opening as shown in Fig. 6, and opened without changing the shape of the chamber 12 within the body so that the liquid content contained within the chamber will freely pass out through the open slit, or mouth, onto the object 40 acted upon, the spreading surfaces of the body and tip then combining to spread the material.

The slit is enabled to be opened with a relatively large opening for the reason that as the tip is turned back it will turn on the back 7 of the body, which remains substantially inflexible, and the tendency will be to lift the upper lip 14 of the slit on a relatively wide arc. The rubber at the point of the slit is made relatively thin so that as the upper lip of the slit is raised the 45 rubber will readily stretch, permitting the upper lip 14 drawing away from the lower lip 15. During this operation the lower lip 15 of the slit will not follow the upper lip owing to the gradually increased thickness of the rubber below the lower 50 55

lip. While there is thus obtained a relatively free delivery of mucilage through the open slit it is a delivery well removed from the sides of the spreading surface within which the slit is contained, so that while the spreading of the mucilage will extend to the sides of the spreading surface it will not extend beyond said surface to make ridges on the object, but will be spread flat at all points.

10 In Fig. 7 a slightly modified structure is shown in that the tip is so positioned that its spreading surface 11 lies normally substantially flush with the spreading surface 9 of the body, the general operation of the cap remaining the same 15 as before. While the form first described is preferred this modified structure has some advantage in that the cap may be used as a spreader without opening the slit or mouth, and little mucilage need be left in the cap after it has 20 been used.

I claim:

1. A spreader cap for adhesive containers applicable to the open end of said containers and comprising a substantially inflexible chambered body, and a tip in extension from said body and bendable thereon, said body and tip having conjoint spreading surfaces, said body having a slit in it in that portion of the body having its spreading surface, said slit being centrally arranged with extension normal to the axis of the cap, and located adjacent the base portion of the tip below the top of the chamber in said body, said portion of the cap within which the slit is contained being relatively thin whereby the slit may be opened by raising its upper lip through stretching of the material adjacent said slit on bending said tip, the portion of said body below said slit being sufficiently inflexible to maintain the lower lip of said slit when the slit is opened as aforesaid.

2. A spreader cap for adhesive containers applicable to the open end of said containers and comprising a substantially inflexible chambered body, a tip in top extension from the back of said body and backwardly bendable thereon, said body and tip having conjoint spreading surfaces, said body having a slit in it in that portion of the body having its spreading surface, said slit being centrally arranged with extension normal to the axis of the cap, and located adjacent the base portion of the tip below the top of the chamber in said body, said portion of the cap within which the slit is contained being relatively thin whereby the slit may be opened by raising its upper lip through stretching of the material adjacent said slit on bending said tip, the portion of said body below said slit being sufficiently inflexible to maintain the lower lip of said slit when the slit is opened as aforesaid.

3. A spreader cap for adhesive containers applicable to the open end of said containers and comprising a substantially inflexible chambered body, a tip in top extension from the back of said body and backwardly bendable thereon, said body and tip having conjoint spreading surfaces, said body having a slit in it in that portion of the body having its spreading surface, said slit being centrally arranged with extension normal to the axis of the cap, and located adjacent the base portion of the tip below the top of the chamber in said body, said portion of the cap within which the slit is contained being relatively thin whereby the slit may be opened by raising its upper lip through stretching of the material adjacent said slit on bending said tip, the portion of said body below said slit gradually decreasing in thickness towards the lower lip of the slit.

GEORGE E. NEALAND.
